UNITED STATES PATENT OFFICE

95,495

DESIGN FOR AUTOMOBILE

Harley J. Earl, Detroit, Mich., assignor to General Motors Corporation, Detroit, Mich., a corporation of Delaware

Application February 13, 1935, Serial No. 55,378

Term of patent 14 years

To all whom it may concern:

Be it known that I, Harley J. Earl, a citizen of the United States, and a resident of Detroit, county of Wayne, State of Michigan, have invented a new, original, and ornamental Design for Automobile, of which the following is a specification, reference being made to the accompanying drawings forming a part thereof.

This application is a continuation in part of my prior application Serial No. D-50,595, filed Feb. 2, 1934.

In the drawings:

Figure 1 is a perspective view of the automobile as it appears when in use, immaterial portions being indicated in broken lines.

Figure 2 is a perspective view of the front of the automobile as it appears when the lamps are in use.

Figure 3 is a front view of the automobile as it appears when the lamps are in use.

Figure 4 is a perspective view of the front of the automobile as it appears when the lamps are not in use.

Figure 5 is a front view of the automobile as it appears when the lamps are not in use.

The dominant feature of the design resides in the front portion of the automobile, as shown in the figures, showing in full lines the lamp elements combined with the fenders and engine hood.

I claim:

The ornamental design for automobile as shown and described.

HARLEY J. EARL.
